UNITED STATES PATENT OFFICE.

CHARLES M. HEUBLEIN, OF CHICAGO, ILLINOIS.

WINDOW ATTACHMENT.

Application filed February 2, 1926, Serial No. 85,585. Renewed November 26, 1926.

This invention relates to certain novel improvements in window attachments and has for its principal object the provision of an improved construction of this character which will be highly efficient in use and economical in manufacture.

Among the salient objects of the invention is the provision of an attachment of this character wherein the attachment has portions movable with a window sash for raising a portion of the window curtain in the direction of movement of the window sash when the window sash is opened for ventilating purposes whereby the raised portions of the window curtain will be remote from the opening prevented by the raising of the window sash.

Other objects will appear hereinafter.

The invention consists in the novel combination and arrangement of parts to be hereinafter described and claimed.

The invention will be best understood by references to the accompanying drawings showing the preferred form of construction and in which:

Fig. 1 is an elevational view of a window showing the invention associated therewith,

Fig. 2 is a sectional view of the same taken substantially on line 2—2 of Fig. 1,

Fig. 3 is a horizontal sectional view of the invention as illustrated in Fig. 2,

Fig. 4 is a typical inner side elevational view of the invention,

Fig. 5 is a sectional detail view taken substantially on line 5—5 of Fig. 2,

Fig. 6 is a sectional detail view taken substantially on line 6—6 of Fig. 4, and

Fig. 7 is an elevational view of a slotted guiding member embodied in the invention.

To accomplish the various objects of the invention I provide a window attachment generally indicated at A which includes opposite similarly constructed guiding structures indicated at B. Each of the guiding structures are adapted to be attached through the medium of suitable attaching elements indicated at 10 to an inner face plate 11 of a window frame 12. This window frame includes an upper window sash 13 and a lower window sash 13' of approved construction.

Each guiding structure includes a body 14 defining a longitudinally extending T-shaped slot 15 slidably receiving a runner strip 16 substantially T-shaped in cross section. This runner strip pivotally carries a sup-

porting arm 17 pivotally connected to the lower end portion of the guiding strip through the medium of a suitable pintle 18. The outer end portion of this supporting arm is connected in a suitable manner to one end of a curtain carrying rod 19.

Forwardly of the pivotal end portion of the supporting arm is rotatably mounted a roller 23 adapted to work in a longitudinally extending guideway 24 formed in the body 14 in parallel relation with the T-shaped slot 15. The lower end portion of this guideway terminates into a semi-circular guideway 25 within which the roller 23 is adapted to work to guide the supporting arm during pivotal movement.

Attached as at 30' to the window sash is a guiding member 30 having a bifurcated portion 31 within which a roller 29 works. This roller is carried by the supporting arm 17 through the medium of a bolt member 28. This arrangement is such that when the window sash is raised the member 30 being movable therewith acts upon the roller 29 and pivots the arm 17 about its pivot 18 moving the carrying rod 19 in engagement with the window curtain 26. During this pivotal movement of the supporting arm the arm is guided by the roller 23 working through the semi-circular guideway 25 forming the lower end portion of the guideway 24.

To further urge pivotal movement of the supporting arm and to guide it during pivotal movement there is provided a guiding plate 20 connected to the pivotal end portion 22' of the supporting arm 17 and provided with a slot 21 concentric with the arc through which the supporting arm pivotally moves. Working in this slot is a roller 22 carried by the body 14 of the guiding structure as at 23'.

As illustrated in the drawings, and as herein indicated, there is attached to the window structure two similarly constructed guiding structures disposed in aligned relation and operative in the following manner.

When the lower sash 13' of the window structure is in its lowermost position the window curtain 26 hangs straight before the window structure with the carrying arm disposed to the rear of the curtain. In raising the window sash the carrying arm is moved in lifting engagement with the lower end portion of the window curtain through the pivotal movement of the sup-

- porting arms effected through the cooperation of the guiding members 30 working on the rollers 29. The supporting arms move about their pivot connection during 5 raising of the lower window sash and swing the carrying rod in a direction so as to fold the lower end portion of the window curtain thereover at which time the rollers 23 have reached the entrance of the guideways 10 24 and by continuous raising of the window sash these rollers working in the guideways cause the supporting arms to move in a straight vertical direction carrying the carrying rod therewith with the lower end portion of the window curtain folded thereon.

- From the description herein and from the brief description relating to the operating of the guiding structures it is apparent that 20 I provide a window attachment operable upon a window curtain to raise a portion of the window curtain remote from the lower sash member of the window sash above and opening provided by raising the window sash.

- It is further apparent that the curtain when supported in a position remote from the opening provided by raising a window sash that the curtain will not be in a position to collect foreign particles gaining entrance through the opening and that the window curtain will not be blown outwardly from the window structure by a draft passing through the opening.

- 35 While I have shown and described the preferred form of construction of my invention, it will be apparent that various changes and alterations may be resorted to during manufacture without departing 40 from the spirit of the invention or the scope of the appended claims.

The invention having thus been set forth, what I claim as new and useful is:—

1. The combination with a movable window sash of a window construction and a curtain for the window construction, of a supporting member movable in engagement with a portion of the curtain and movable in a direction of movement of the window sash, operating means movable with the sash, and a connection between the operating means and the supporting member, substantially as described.

2. The combination with a movable window sash of a window construction and a curtain for the window construction, of a supporting member movable through an arc of a circle in engagement with a portion of the window curtain for raising the window 55 curtain upon movement of the movable sash, operating means movable with the sash, and a connection between the operating means and the supporting member.

3. The combination with a window sash 60 of a window construction and a curtain for

the window construction, of a supporting member movable in engagement with the lower end portion of the curtain for moving said lower end portion of the curtain in a direction away from the window construction and upwardly with respect thereto, operating means movable with the window sash, and a connection between the operating means and the supporting member. 70

4. The combination with a window sash 75 of a window construction and a curtain for the window construction, of means movable in engagement with a portion of the curtain for raising the curtain above an opening provided by raising the window sash, and means movable with the window sash for moving said raising means into engagement with the curtain and for moving said raising means in a direction to raise the curtain. 80

5. The combination with a window sash 85 of a window construction and a curtain for the window construction, of means movable in engagement with a portion of the curtain for raising the curtain above an 90 opening provided by raising the window sash, means for guiding the raising means in engagement with the curtain and during movement of the raising means to raise the curtain, and means movable by raising of 95 the window sash for moving said raising means.

6. A window attachment including a member movable in engagement with a window curtain and movable in a direction to 100 raise a portion of the curtain, and means for moving said member, said means including guiding means, supporting arms pivotally carried by the guiding means and carrying the member, and means engaging 105 the supporting arms and movable with a window sash to pivot said arms and move said guiding means to raise the portion of the curtain.

7. The combination with a window sash, 110 of a structure of the class described including a fixed body defining spaced longitudinally extending slots, a guiding member working in one of the slots, an arm pivotally carried by the guiding member for movement therewith and including a portion working in the other of the slots, a supporting member carried by the arm for engagement with a portion of a window curtain, and an operating member for the arm carried for movement with the window sash. 115

8. The combination with a window sash, and a window structure, of a structure of the class described including a body fixed to the window structure and defining spaced longitudinally extending slots, a guiding member working in one of the slots, an arm pivotally carried by the guiding member for movement therewith and including a portion working in the other of the slots, a sup- 120 125 130

- porting member carried by the arm for engagement with a portion of a window curtain, and an operating member for the arm carried for movement with the window sash.
- 5 9. The combination with a window sash and a window structure, of a structure of the class described including a body fixed to the window structure and defining a slot substantially T-shaped in cross section and a
- 10 slot extending parallel with the T-shaped slot provided with a semi-circular end portion, a guiding member substantially T-shaped in cross section working in the T-shaped slot, an arm pivotally carried by the
- 15 guiding member and including a portion working in the second mentioned slot and adapted to pivot about its pivotal connection to the guiding member when the portion works through the semi-circular portion
- 20 of the second mentioned slot and be extended in a horizontal plane when the portion works through the remaining portion of the second mentioned slot, a curtain supporting member carried by the arm, a slotted member
- 25 carried by the window sash for movement therewith, and a member carried by the supporting arm engaging the slot of the slotted member and coacting with the portion working in the second mentioned slot
- 30 for pivoting the arm about its pivotal connection and for moving the guiding member longitudinally of the T-shaped slot when the slotted member is moved with the window sash.
- 35 10. A curtain operating attachment for a window having a vertically movable sash, which includes a swinging frame adapted to engage the intermediate portion of a curtain hanging in front of the sash, means for bodily raising and lowering said frame in response to the respective raising and lowering of the sash, and means for swinging the frame to fold and unfold the lower end of the curtain when the sash is respectively
- 40 raised and lowered.
- 45 11. In combination with a window having a vertically movable sash and a curtain hanging in front of the sash, a swinging frame adapted to engage the intermediate portion of the curtain, means for bodily raising and lowering the frame in response to the respective raising and lowering of the sash, and means for swinging the frame to-
- ward and away from the window at the initial raising and final returning movement respectively of the sash.
- 55 12. In combination with a window having a vertically movable sash and a curtain, a pivoted curtain raising element adapted to engage said curtain and means for rotating said curtain raising element in response to the raising and lowering of said sash.
- 60 13. In combination with a window having a vertically movable sash and a curtain, a curtain raising element adapted to engage said curtain, and means for raising and lowering said curtain raising element, in response to the raising and lowering of the sash, through a distance greater than the
- 65 distance of excursion of the sash.
- 70 14. In combination with a window having a vertically movable sash and a curtain, a curtain raising member adapted to engage the curtain intermediate top and bottom of the curtain, and means for lifting said curtain raising member, in response to the initial upward movement of the sash, through an excursion of greater length than the corresponding initial excursion of the sash, and for continuing the upward movement of the
- 75 curtain raising member thereafter at substantially the same rate as the continued upward movement of the sash.
- 80 15. In combination with a window having a vertically movable sash and a curtain, a curtain raising member adapted to engage the curtain intermediate top and bottom of the curtain, said member including pivoted supporting levers and means for rotating said supporting levers in response to the initial upward movement of the sash, through a predetermined arc and for thereafter constraining the curtain raising member to upward movement in response to the continued upward movement of the sash.
- 85 16. In combination with a window having a vertically movable sash and a curtain, a curtain raising element associated with said window and movable in relation to said window and sash, and adapted to engage said curtain, and means for raising and lowering said curtain raising element in response to the raising and lowering of said sash.
